UNITED STATES PATENT OFFICE.

WILLIAM H. PIKE, JR., OF ORANGE, NEW JERSEY, ASSIGNOR TO NEW YORK ADDING TYPEWRITER COMPANY OF ORANGE, NEW JERSEY, A CORPORATION OF MISSOURI.

HANGER FOR TYPE-BARS.

No. 813,664.

Specification of Letters Patent:

Patented Feb. 27, 1906.

Application filed January 11, 1904. Serial No. 188,536.

To all whom it may concern:

Be it known that I, WILLIAM H. PIKE, Jr., a citizen of the United States, residing at Orange, Essex county, New Jersey, have invented certain new and useful Improvements in Hangers for Type-Bars, of which the following is a specification.

This invention relates to hangers for the type-bars of type-writing machines, and has for its object the provision of a hanger which shall be simple and inexpensive in construction and furnish a ready means of adjustment for the bearings for the type-bars.

The invention can be best explained in connection with the accompanying drawings, of which—

Figure 1 is an elevation, partly in section, of a portion of a type-writing machine sufficient to show the mounting of a hanger and type-bar. Fig. 2 is an enlarged vertical longitudinal section of the hanger. Fig. 3 is an enlarged section on the line *a b* of Fig. 2 looking in the direction of the arrow, and Fig. 4 is an enlarged section on the line *c d* of Fig. 2 looking in the direction of the arrow.

The frame of the machine (not shown) supports the upper and lower arc-plates 10 and 11 and a paper-carriage (not shown) carrying a cylindrical platen 22. About the arc-plates are distributed the type-bars and their accompanying hangers and operating mechanism in a manner as is well understood, and the type-bar and its mechanism, which will now be described, are typical of each of them.

The type-bar 19 is hung in a hanger A, secured to the lower arc-plate; said bar carrying a type-head into and out of contact with paper upon the platen 22, the writing position of the bar being shown in dotted lines. Fig. 1. To the type-bar is pivoted a connecting-bar 20, which at its other end is pivoted to the vertically-movable guide-bar 14, mounted between rollers 13 in brackets 12. The brackets are secured to the arc-plates, holes being provided in the bottoms of the brackets and in the arc-plates to permit the passage of the guide-bar. Rigidly secured to the guide-bar is a key lever or stem 17, which carries the keys 18. A spring 21 for maintaining the type-bar in inoperative position, full lines of Fig. 1, is secured to the stem 17 and the upper arc-plate.

The hanger A comprises two vertical plates

23 and 24, resting upon the arc-plate 11 and secured together by suitable fastenings—such as rivets 25, 26, 27, 28, and 29—having shoulders which bear against the inner face of the plates and separate them by the proper distance, Fig. 4. Resting upon the plates 23 and 24 is a securing cap-plate 30, which extends around the arc-plate over the hangers and is secured to the lower arc-plate by bolts, as shown. At one end of the hanger the plates are tapered, as shown, Figs. 1 and 2, and in their tapered ends have tapered holes, Fig. 3, adapted to receive the tapered journals 35 and 36 on the hub 37 of the type-bar 19, and thereby form bearings on which the bar may swing. All the rivets 25, 26, 27, 28, and 29 act to hold the plates at the proper distance apart; but the rivets 25, 26, and 27 by reason of their arrangement with relation to the bearings of the type-bar may also be employed to adjust those bearings. It will be noted that the rivets are arranged at different distances from the bearings. If the rivet 27, which is the more remote fastening, be tightened, plates 23 and 24 will draw across the shoulders of rivets 25 and 26 as fulcrums, and the outer ends of the plates will be moved away from each other, thus loosening the bearings, while if rivets 25 and 26, which constitute the nearer fastening, be tightened the outer ends of the plates will be drawn together, thus tightening the bearings. It will be seen that as the journals of the type-bars are tapering if they should become worn any lost motion may be overcome by tightening the rivets 25, 26 and bringing the ends of the plates 23 and 24 closer together.

Without limiting myself to the precise construction and arrangement of parts shown and described, I claim—

1. In a type-writing machine, the combination of plates, a type-bar having bearings in said plates, and fastenings for securing said plates placed at different distances from said bearings, the whole being so constructed and arranged that tightening the fastening nearer the type-bar bearings operates to tighten said bearings and tightening the fastening more remote from said bearings operates to loosen the bearings, substantially as described.

2. In a type-writing machine, the combi-

nation of plates, a type-bar having bearings in said plates, and fastenings for securing said plates so arranged with relation to said bearings that when one of said fastenings is tightened the other will act as a fulcrum on which said plates rock to loosen said bearings, and when the latter fastening is tightened, the former will act as a fulcrum on which said plates rock to tighten said bearings, substantially as described.

3. In a type-writing machine, the combination of plates, a type-bar having bearings in said plates and shouldered rivets for securing said plates arranged at different distances from said bearings, substantially as described.

4. In a type-writing machine, a type-bar hanger comprising two plates and rivets having shoulders engaging the inner faces of the plates for connecting them in separated relation, said plates having tapered holes near their ends, combined with a type-bar having a hub to fit between said plates and tapered journals projecting from the sides of said hub to fit in said holes, substantially as described.

5. In a type-writing machine, the combination with a type-bar having journals pro-

jecting from the sides thereof, of a hanger having side plates provided with bearings for said journals, a pair of rivets connecting said plates adjacent the bearings for the type-bar journals, and a single rivet connecting said plates at a greater distance from the type-bar bearings and in a plane between the aforesaid rivets, substantially as described.

6. In a type-writing machine, the combination with a type-bar having journals projecting from the sides thereof, of a hanger having side plates provided with bearings for said journals, a pair of rivets connecting said plates at points in the same vertical plane, and a single rivet connecting said plates at a point in a horizontal plane between the aforesaid rivet and in a vertical plane more remote from the type-bar bearings than said pair of rivets, substantially as described.

In testimony whereof I have signed my name to this specification in the presence of two subscribing witnesses.

WILLIAM H. PIKE, JR.
